NURSERY FURNITURE

Chauncey R. Curr and Alberta E. Curr,
San Diego, Calif.

Application December 24, 1946, Serial No. 718,148

3 Claims. (Cl. 5—2)

1

This invention relates to nursery furniture, and more particularly to a combined bed, safety pen and wardrobe cabinet, which can be used with a new born baby until he is two or three years old.

It is an object of the present invention to make easy the caring of a baby for the mother, whereby without lifting or stooping, the baby can be handled easily at times of feeding, changing of clothing and bathing.

It is another object of the present invention to provide a combined baby safety pen and cabinet for a nursery which is so constructed that the safety pen can be easily separated from the cabinet part, folded and easily transported in an automobile so as to be used as a safety pen on a floor or ground surface, and wherein the safety pen has a bottom that serves as a bed on which the child may lie or play, and wherein when the child outgrows the safety pen and bed, it may be removed from the cabinet structure and the cabinet structure can still be used thereafter as a useful piece of furniture.

For other objects and for a better understanding of the invention, reference may be had to the following detailed description taken in connection with the accompanying drawings, in which:

Figure 1 is a front elevational view of the combined bed, safety pen and cabinet.

Figure 2 is an end elevational view of the cabinet with one of the drawers pulled out and with the safety pen and bed mounted thereon.

Figure 3 is a fragmentary front elevational view of the safety pen after it has been folded upon the bed surface in condition to be removed from the cabinet structure for the purpose of transport or storing.

Figure 4 is a fragmentary cross-sectional view taken on line 4—4 of Figure 1, and looking in the direction of the arrows thereof.

Figure 5 is an enlarged transverse cross-sectional view taken on line 5—5 of Figure 1, and looking in the direction of the arrows thereof, and showing the hinge connection of one of the front gates to an end of the pen.

Figure 6 is an enlarged cross-sectional view looking upon the hinge connection for connecting the two gates together and with a removable hinge pin to permit their separation from one another when it is desired that the gate be folded outwardly and over the outside of the respective ends of the safety pen.

Referring now to the figures, 10 represents a cabinet structure in which are disposed drawers 11, 12 and 13, and a cupboard closet adapted to

2

be closed by a door 14. The side posts of the cabinet have casters 15 on their lower ends whereby the cabinet can be rolled over the floor surface. On one end of the cabinet is a container or waste can 16 for the immediate disposal of wet diapers. Also, on the same end of the cabinet is a rail 17 over which clean diapers may be hung. The cabinet structure 10 has a flat top 18 to which the combined bed surface and safety pen 19 is connected by means of fasteners 21 at the ends thereof.

This combined bed surface and pen comprises a bed surface 22 which serves as a floor for the pen. This floor surface is covered with light grade linoleum and can be easily cleaned.

The combined bed surface and safety pen 19 includes end walls 23 and 24, a back wall 25 which extends the full length of the pen, and two front gates 26 and 27 which unite at the center of the pen and which are adapted to be swung outwardly and around and back against the outside of the respective ends 23 and 24. The hinge connections of the gates with the forward edges of the end walls are shown at 28 in Figure 5. It will be noted that the hinge joint is on the end of an angle bracket portion 29 secured to the edge of the end wall 24 by screws 31. The joining hinge plate, as indicated at 32, for the gate is connected to the gate by screws 33. The gates 26 and 27 swing over the floor or bed surface 22. Latch bolts 34 and 35 connect the inner ends of the gates to the floor 22. The upper ends of the gates 26 and 27 are held together by the union of hinge plates 36 and 37 and a removable hinge pin 39 slidable through a guide 41 and operated by a handle 42, Figure 6.

The end wall 23 is hinged to the bed surface 22 by hinges 44, Figures 3 and 4, so that when the gate 26 has been swung outwardly and against the outside of the end wall 23, the end wall and gate can be swung inwardly and downwardly to rest upon the bed surface 22, as shown in Figure 3. On the other end of the floor surface is a riser 45 to which end wall 24 is pivoted for similar downward movement by hinges 46. The end wall 24 and the gate 27 which has been swung outwardly and onto the outside of the end wall will have their upper ends rest upon the upper ends of the end wall 23 and gate 26 when these parts have been folded inwardly and downwardly, Figure 3. The end walls 23 and 24 are detachably connected by hinge plates 47 and 48 and a removable hinge pin 49 to a back wall 25 which extends the full length of the pen. This back wall 25 is pivoted upon a riser 51 for inward pivotal

3

movement so that it can be folded down on top of the other parts, as shown in Figure 3. The pivot connection is effected by means of hinges 52, Figure 4.

According to Figure 6, the handle 42 is so situated on the hinge pin 39 as to prevent the latter from becoming disengaged from the guide 41 even though the pin is lowered as far as the handle 42 will permit. However, when the hinge pin 39 is elevated to a point where the handle 42 is brought into engagement with the guide 41, the lower end of the hinge pin will become disengaged from the loop 54 of the hinge section 37 but will be retained in the uppermost loop 55 of the hinge section 36. Thus the hinge sections may be disconnected one from the other by lifting the hinge pin as far as it will go.

It will now be apparent that there has been provided a compact and folded structure which can be removed from the cabinet 10 for the purpose of being transported to a different location. The folded pen can be placed in an automobile and taken away for picnics, vacations, and extended visits. The bed which is the surface 22 and which is a part of the pen is removable from the cabinet structure 10. Even though the child has outgrown the bed and pen, the cabinet can still be used as a useful piece of furniture. In case of sickness or for sun bathing, one end of the bed and pen can be left fastened to the top of the cabinet and the other end raised to a reasonable height to provide an inclined bed surface. Additional working surface can be provided by pulling out slides 54 of the cabinet.

Having now described our invention, we claim:

1. A foldable and demountable crib comprising a main base having a flat top, a secondary base comprising a plate resting removably upon said main base top, means removably securing said secondary base in place on said main base top, a first vertical end wall comprising a plate resting upon said secondary base plate, a second end wall comprising a riser fixed on said secondary base plate and a second wall plate resting upon said riser, hinge means at the lower edges of said first and second end wall plates hinging the same to said secondary base plate and said riser, respectively, whereby said first end wall can be folded inwardly to rest upon said secondary base plate and said second end wall plate can be folded inwardly to rest upon the inwardly folded first end wall plate, a front wall comprising a pair of front vertical plates resting their lower edges upon said secondary base plate, latch means releasably securing the adjacent inward edges of said front plates together, means on the outward edges of said front plates hinging said front plates to the forward edges of said first and second end wall plates whereby said front plates can be swung forwardly to provide frontal access to said secondary base plate with said latch means released and whereby said front plates can be swung outwardly and rearwardly to lie along the outward sides of said end wall plates both in the vertical and in the reclining folded positions of said end wall plates, a vertical rear wall comprising a riser fixed on said secondary base plate and a rear wall plate hinged at its lower edge on the upper edge of said riser to swing forwardly and downwardly to rest upon the front wall plate folded onto the related second end wall plate, releasable catch means connecting the rear edges of said end wall plates to the opposite end edges of said rear wall plate in vertical positions thereof, the dimensions and thicknesses of said end wall and front wall plates and the heights of said risers being proportioned to permit the folded end walls and front plates to lie parallelly upon each other and the folded rear wall plate to lie parallelly thereon in a compact form lying substantially entirely within the edges of said secondary base plate.

2. A foldable and demountable crib comprising a main base having a flat top, a secondary base comprising a plate resting removably upon said main base top, means removably securing said secondary base in place on said main base top, a first vertical end wall comprising a plate resting upon said secondary base plate, a second end wall comprising a riser fixed on said secondary base plate and a second wall plate resting upon said riser, hinge means at the lower edges of said first and second end wall plates hinging the same to said secondary base plate and said riser, respectively, whereby said first end wall can be folded inwardly to rest upon said secondary base plate and said second end wall plate can be folded inwardly to rest upon the inwardly folded first end wall plate, a front wall comprising a pair of front vertical plates resting their lower edges upon said secondary base plate, latch means releasably securing the adjacent inward edges of said front plates together, means on the outward edges of said front plates hinging said front plates to the forward edges of said first and second end wall plates whereby said front plates can be swung forwardly to provide frontal access to said secondary base plate with said latch means released and whereby said front plates can be swung outwardly and rearwardly to lie along the outward sides of said end wall plates both in the vertical and in the reclining folded positions of said end wall plates, a vertical rear wall comprising a riser fixed on said secondary base plate and a rear wall plate hinged at its lower edge on the upper edge of said riser to swing forwardly and downwardly to rest upon the front wall plate folded onto the related second end wall plate, releasable catch means connecting the rear edges of said end wall plates to the opposite end edges of said rear wall plate in vertical positions thereof, the dimensions and thicknesses of said end wall and front wall plates and the heights of said risers being proportioned to permit the folded end walls and front plates to lie parallelly upon each other and the folded rear wall plate to lie parallelly thereon in a compact form lying substantially entirely within the edges of said secondary base plate.

3. A foldable and demountable crib comprising a main base having a flat top, a secondary base comprising a plate resting removably upon said main base top, means removably securing said secondary base in place on said main base top, a first vertical end wall comprising a plate resting upon said secondary base plate, a second end wall comprising a riser fixed on said secondary base plate and a second wall plate resting upon said riser, hinge means at the lower edges of said first and second end wall plates hinging the same to said secondary base plate and said riser, respectively, whereby said first end wall can be folded inwardly to rest upon said secondary base plate and said second end wall plate can be folded inwardly to rest upon the inwardly folded first end wall plate, a front wall comprising a pair of front vertical plates resting their lower edges upon said secondary base plate, latch means releasably securing the adjacent inward edges of said front plates together, means on the outward edges of said front plates hinging said front plates to the forward edges of said first and second end wall plates whereby said front plates can be swung forwardly to provide frontal access to said secondary base plate with said latch means released and whereby said front plates can be swung outwardly and rearwardly to lie along the outward sides of said end wall plates both in the vertical and in the reclining folded positions of said end wall plates, a vertical rear wall comprising a riser fixed on said secondary base plate and a rear wall plate hinged at its lower edge on the upper edge of said riser to swing forwardly and downwardly to rest upon the front wall plate folded onto the related second end wall plate, releasable catch means connecting the rear edges of said end wall plates to the opposite end edges of said rear wall plate in vertical positions thereof, the dimensions and thicknesses of said end wall and front wall plates and the heights of said risers being proportioned to permit the folded end walls and front plates to lie parallelly upon each other and the folded rear wall plate to lie parallelly thereon in a compact form lying substantially entirely within the edges of said secondary base plate.

outward sides of said end wall plates both in the vertical and in the reclining folded positions of said end wall plates, a vertical rear wall comprising a riser fixed on said secondary base plate and a rear wall plate hinged at its lower edge on the upper edge of said riser to swing forwardly and downwardly to rest upon the front wall plate folded onto the related second end wall plate, releasable catch means connecting the rear edges of said end wall plates to the opposite end edges of said rear wall plate in vertical positions thereof, the hinge means connecting said front wall plates with the forward edges of said end wall plates preventing rearward swinging of said front wall plates from a coplanar relation, and releasable detent means operating between the lower edges of said front wall plates and said secondary base to prevent forward front wall plate and the end wall plates to which they are hinged from

shifting forwardly or rearwardly relative to said secondary base plate.
